[57] CLAIM

The ornamental design for a pliable, book-holding platform for attachment to a vehicle steering wheel, as shown and described.

DESCRIPTION

FIG. 1 is a front elevational view of a pliable, book-holding platform for attachment to a vehicle steering wheel showing my new design, the book and steering wheel depicted by means of broken lines being shown for illustrative purposes only and forming no part of the claimed design;

FIG. 2 is a front elevational view thereof;

FIG. 3 is a rear elevational view thereof;

FIG. 4 is top plan view thereof;

FIG. 5 is a bottom plan view thereof;

FIG. 6 is a right side elevational view thereof; and,

FIG. 7 is a left side elevational view thereof.
